(57) CLAIM

The ornamental design for a soap holder, as shown and described.

DESCRIPTION

Soap holder

FIG. 3.1 is an exploded view, showing my new design.

FIG. 3.2 is a top perspective view thereof.

FIG. 3.3 is a bottom plan view thereof with the cap removed.

FIG. 3.4 is a front side elevational view thereof, the back side being a mirror image of the same.

FIG. 3.5 is a top plan view thereof with the cap removed. The broken lines depict portions of the soap holder that form no part of the claimed design.
